CLAIM

The ornamental design for a wind deflector for vehicles, as shown and described.

DESCRIPTION

FIG. 1 is a front perspective view of a wind deflector for vehicles showing my new design;

FIG. 2 is a side elevation view thereof, it being understood that the broken lines are for illustrative purposes only;

FIG. 3 is a front elevation view thereof;

FIG. 4 is a top plan view thereof;

FIG. 5 is a rear elevation view thereof;

FIG. 6 is a bottom plan view thereof; and

FIG. 7 is a front perspective view of a wind deflector for vehicles showing a second embodiment of my new design, wherein the sole difference resides in the configuration of the top central surface thereof.
